STROLLER OR SIMILAR ARTICLE

Jacob Berger, New York, N. Y.

Application August 16, 1949, Serial No. 4,524

Term of patent 14 years

(Cl. D14—14)

To all whom it may concern:

Be it known that I, Jacob Berger, a citizen of the United States, residing at New York, in the county of New York and State of New York, have invented a new, original, and ornamental Design for a Stroller or Similar Article, of which the following is a specification, reference being had to the accompanying drawing, forming part thereof.

In the drawing:

Fig. 1 is a perspective front view of a stroller or similar article, showing my new design;

Fig. 2 is a front elevational view thereof; and,

Fig. 3 is a side elevation of the stroller or similar article shown in Fig. 1.

The characteristic features of my design are shown in the drawing in full lines.

I claim:

The ornamental design for a stroller or similar article, as shown and described.

JACOB BERGER.
